MACHINE FOR TRAINING STUDENT PILOTS
IN HANDLING AIRPLANES

Frederick L. Fox, Washington, D. C.

Application May 17, 1938, Serial No. 208,462

11 Claims. (Cl. 244—84)

This invention relates to machines for training student pilots in handling airplanes, and the primary object of the present invention is to provide features capable of embodiment in a training machine adapted to solely travel upon the ground for use as a primary training machine, or capable of embodiment in a machine adapted for flight to afford advanced training.

Another object of the present invention is to provide a training machine of the above kind having two independent sets of movable controlling planes, one set being adapted to be operated for the purpose of creating unfavorable conditions such as may be met with in actual flight, and the other set being under the control of the student pilot so that he may receive training in overcoming these unfavorable conditions. It is contemplated to provide means for operating the first-mentioned set of controlling planes either mechanically or manually. When manual operating means is provided for the first-mentioned set of controlling planes, the latter are preferably of such a character as to enable the instructor pilot in charge thereof to take control of the machine away from the student pilot in an emergency. For this purpose, the present invention further contemplates providing the said first-mentioned set of controlling planes so that they have greater controlling power than the second-mentioned set of controlling planes. On the other hand, in the ground-type of machine, wherein one set of controlling planes is mechanically operated, that set is preferably of the form or arrangement to have a lesser controlling power than the set controlled by the student pilot, so that the student pilot may have actual control over the machine as is necessary in the absence of an instructor pilot.

The present invention is essentially identified with machines capable of free travel, as opposed to machines of the captive type having restraining means restricting direction of travel, etc. Accordingly, a training machine embodying the present invention is in the general form and construction of an airplane having propelling means and capable of free movement on the ground or in the air, depending upon whether the machine is adapted for primary ground training or advance free flight training.

A still further object of the present invention is to provide, in the type of training machine adapted for free flight, means for giving the student control over any one or more of the sets of secondary controlling planes, and to pro-

vide means, operable by the instructor pilot, for quickly rendering such controls inoperable by the student pilot in case of an emergency. An advantage of this provision is that advance training may be given in stages or degrees as the student pilot improves in his ability to handle the machine, at the same time making it possible for the instructor pilot to take charge of the machine in an emergency and avoid a disaster.

With the above general objects and features in view, and others that will become apparent as the nature of the invention is better understood, the present invention consists in the novel form, combination and arrangement of parts hereinafter more fully described, shown in the accompanying drawings and claimed.

In the drawings:

Figure 1 is a top plan view, somewhat diagrammatic, of a machine embodying the present invention adapted for free travel upon the ground and for use as a primary ground training machine.

Figure 2 is a side elevational view of the machine shown in Figure 1.

Figure 3 is a front elevational view thereof.

Figure 4 is an enlarged fragmentary longitudinal section on line 4—4 of Figure 1.

Figure 5 is a fragmentary transverse section taken on line 5—5 of Figure 4.

Figure 6 is a diagrammatic perspective view showing the arrangement of the sets of movable controlling planes employed in the machine of Figure 1, together with the operating means therefor.

Figure 7 is a view similar to Figure 2 of a machine of the type adapted for free flight, embodying the present invention.

Figure 8 is a top plan view of the machine shown in Figure 7.

Figure 9 is a view similar to Figure 6 of the controlling planes and operating means therefor forming part of the machine shown in Figure 7.

Figure 10 is a fragmentary top plan view illustrating a modified arrangement of the sets of movable controlling planes.

Figure 11 is a fragmentary perspective view showing a still further modification of the arrangement of movable controlling planes.

Figure 12 is a view similar to Figure 9 illustrating a modification of the free flight machine of Figure 7 with respect to the means for operating the two sets of movable controlling planes, whereby the student pilot may be given con-

trol of any desired one or more of the sets of primary controlling planes, and whereby the instructor pilot may render such controlling planes inoperable by the student pilot, at will.

6 Figure 13 is a fragmentary view partly in side elevation and partly in longitudinal section, illustrating details of the operating means forming part of the modification shown in Figure 12.

10 Figure 14 is an enlarged horizontal section on line 14—14 of Figure 13.

Figure 15 is a fragmentary vertical section on line 15—15 of Figure 13.

15 Figure 16 is an enlarged perspective view of the lever forming part of the means for enabling the instructor pilot to render the primary elevator planes inoperable by the student pilot.

20 Figure 17 is an enlarged perspective view of the lever forming part of the means for enabling the instructor pilot to render the primary set of ailerons inoperable by the student pilot.

25 Figure 18 is a view similar to Figure 16 of the lever forming part of the means shown in Figure 14 for enabling the instructor pilot to render the primary vertical rudder inoperable by the student pilot; and

Figure 19 is an enlarged fragmentary section on line 19—19 of Figure 13.

Referring to the drawings, the embodiment or form of the invention shown in Figures 1 to 6 inclusive is in the general form and construction of an airplane of the monoplane type, although not adapted for flight and only being intended for and capable of free travel upon the ground. This embodiment includes a body or fuselage 5 having laterally extending wing-like supports 6 which are not intended or constructed to act as sustaining planes for free flight but merely act as supports for ailerons as will be presently described. In the center line of the body or fuselage 5, approximately at the center of gravity, a single 30 downwardly opening pocket 1 is formed, and in this pocket there is mounted a single supporting and driving wheel 8. This wheel is preferably provided with a pneumatic tire and is non-retractable, and is shown as being driven by a suitable 35 engine or motor 9 mounted within the forward portion of the body or fuselage 5 and operatively connected with the wheel 8 by suitable chain or other gearing 10.

40 The machine is provided with the usual movable controlling planes including ailerons 11 carried by the wing-like supports 6, elevators or horizontal rudders 12 carried by the tail end of the body or fuselage 5, and a vertical rudder 13 for lateral steering. 45 The lateral steering is also carried by the tail end of the body or fuselage 5 intermediate the elevators 12. This set of ordinary movable controlling planes is provided with the usual well known or any preferred form of manual operating means, the operating means illustrated including the usual lever or joy stick 14 for manipulating the ailerons 11 and elevators 12, and an ordinary foot lever 15 for actuating the vertical steering rudder 13. The connections between the hand lever 14 and foot lever 15 and the respective steering and controlling planes 11, 12 and 13 include suitable cables as illustrated clearly in Figure 6, and are of ordinary or well known type. The control levers 14 and 15 are arranged as usual within the body or fuselage 5 in front of a seat 16 adapted to be occupied by the student pilot so that he may conveniently manipulate the steering and controlling planes 11, 12 and 13.

50 The wheel 8 serves not only as a running support for the machine but also as a pivotal sup-

port on which it may tilt laterally or vertically, i. e., in a fore and aft direction. It will thus be seen that substantially the same degree of skill is required to "balance" the ground training machine while traveling on the single supporting wheel at a predetermined speed over the ground, as is required to balance an airplane laterally and longitudinally while in free flight.

55 In order to create unfavorable conditions such as are met with or encountered during actual flight, I provide a secondary set of controlling planes including auxiliary ailerons 11a, and auxiliary horizontal rudders or elevators 12a, adapted to be operated for the purpose of creating conditions which must be overcome by the student 60 pilot through operation of the control levers 14 and 15 and consequent actuation of the primary steering and controlling planes 11, 12 and 13. In order to give the student absolute control of the machine at all times, the controlling planes 11 and 12 have a controlling power which predominates that of the secondary or auxiliary controlling planes 11a and 12a. This may be accomplished by giving the primary controlling planes 11 and 12 a greater degree of movement, 65 greater area, and/or greater controlling leverage than that of the auxiliary controlling planes 11a and 12a, the greater area being provided by simply making the controlling planes 11 and 12 of greater size or area than that of the auxiliary 70 planes 11a and 12a, and/or the greater controlling leverage being simply provided by placing the primary controlling planes 11 a greater distance from the longitudinal center of the fuselage 5 than the planes 11a, and extending the planes 12 laterally from such longitudinal center a greater distance, as shown. In the construction of 75 Figure 1, the secondary controlling planes 11a are made of smaller size or lesser area than the primary controlling planes 11, and are arranged on the rear edge of the support 6 inwardly of the primary controlling planes 11 nearer the longitudinal axis of the fuselage. Thus, the primary controlling planes 11 are of greater controlling leverage and area than the secondary controlling planes 11a. Substantially the same condition 80 maintains with respect to the secondary controlling planes 12a as compared with the corresponding primary controlling planes or elevators 12. The latter, however, may be conveniently placed rearwardly of the secondary elevators 12a 85 as shown clearly in Figures 1 and 6, and while both greater leverage and pressure area may be utilized, either way may be used alone for enabling the primary controlling planes 11 and 12 to have a controlling effect which predominates over the controlling effect of the secondary controlling planes 11a and 12a. In the case of biplanes, the primary ailerons 11' may be provided on the upper supporting planes or wings 6a, and the secondary ailerons 11' may be provided on 90 the lower supporting planes or wings 6b, as shown in Figure 11. Predominating controlling influence is provided for the primary ailerons 11' in this arrangement by simply making the latter of greater area. As shown in Figure 10, the primary ailerons 11' may be provided on the supporting plane or wing 6c of a monoplane and provided with a cut-out 16 within which the secondary aileron 11' is arranged, the primary aileron 11' being of greater size and leverage.

95 While the secondary controlling planes 11a and 12a may be manipulated by an instructor pilot seated in the machine in front of the student pilot, I have shown the secondary controlling planes 11a and 12a as provided with

mechanical operating means. This mechanical operating means may consist of a rotatable member 17 mounted in the forward portion of the body or fuselage 5 adjacent the engine 9 and driven slowly by the latter through a suitable gearing 18, the rotatable member 17 having a side cam groove 19 engaged by one end of a rod 20 operatively connected with the secondary elevators 12a. The rotatable member 17 further has a peripheral cam groove 21 engaged by an end of a rod 22 operatively connected with the secondary ailerons 11a, and by driving the rotatable member 17, the secondary controlling planes 11a and 12a may be periodically actuated in a predetermined manner and slowly to create extended unfavorable conditions such as are met with in actual flight. Thus, the student pilot must operate the control levers 14 and 15 so as to actuate the primary controlling planes 11 and 12 for overcoming these unfavorable conditions and thereby familiarizing himself with the control of the machine. This is of course carried out while the machine is in motion or being driven about upon the ground through the medium of the driving and supporting wheel 8 driven by the engine 9. In this way, the student pilot may be given primary training in the handling of airplanes with comparative safety and no danger of disastrous crashes such as often occur when primary training is attempted in actual flight. As the machine is capable of free movement along the ground unrestricted by any towing or guiding means, the student must of course have full control at all times of lateral steering through operation of the vertical rudder 13, and no secondary vertical steering rudder is provided to be opposed by the student pilot. In actual practice, any suitable or well known means may be provided for unclutching the driving and supporting wheel 8 from the engine 9, and it is also desired to have a clutch 23 in the driving connection between the motor 9 and the rotatable cam member 17. Thus, the secondary controlling planes 11a and 12a may be left stationary in the very first lessons which are given to the student pilot, so that he can initially simply get the "feel" of the steering and controlling means. As the student progresses, the mechanical means for actuating the secondary controlling planes may be utilized to set up the unfavorable conditions mentioned which are to be opposed by the student pilot through actuation of the primary controlling planes. Also, the clutch 23 may have suitable actuating means within convenient reach of the student pilot occupying the seat 16 so as to throw this mechanical actuating means out of operation at will. Naturally, a very desirable amusement device would be afforded by a machine constructed as illustrated in Figures 1 to 6 inclusive, with the secondary controlling plane and the mechanical actuating means therefor omitted.

It is desirable to provide anti-friction means on the outer end of the supports 6 or the outer primary ailerons 11, capable of engaging the ground if the machine should tilt laterally to an undue degree, so that the forward travel of the machine will not be interfered with and whereby proper support for the machine is provided in a laterally tilted position when the machine is not in motion. Such anti-friction means may consist of small wheels 24 journaled on the undersides of the primary ailerons 11, with the lower portions thereof considerably above the tread plane of the central driving and support-

ing wheel 8, as well as slightly rearwardly of the latter. As will be seen from Figure 3, the lateral angle between the horizontal and lines drawn from the tread point of the wheel 8 to the wheels 24, is of a predetermined degree so as to enable the same to operate at the best advantage in acting as balancers or lateral tilt limiting means. In other words, the wheels 24 are supported with their ground-engaging portions above the tread plane of the wheel 8 to form lateral base angles for banking when turning as the machine travels along the ground. By providing the wheels 24 on the movable ailerons 11, the latter may be manipulated so as to forcibly raise that support 6 which has been lowered through lateral tilting of the machine, thereby bringing the machine quickly back to a state of lateral equilibrium.

The embodiment or form of the invention shown in Figures 7 to 9 inclusive is in the general form and construction of an airplane of the monoplane type adapted for actual free flight for use in giving advanced or free flight training. This embodiment includes a body or fuselage 5a having laterally extending wings 6a constructed to act as sustaining planes, and provided with suitable landing gear 25 and tail skid or wheel 26 common to conventional airplane construction. The machine also has the usual motor-operated propeller 27 and complete standard steering and controlling equipment including primary ailerons 11a, primary elevators or horizontal rudders 12a and primary vertical steering rudder 13a. The primary steering and controlling planes 11a, 12a and 13a have conventional manual operating means, such as the ordinary lever or joy stick 14a for actuating the ailerons 11a and elevators 12a, and the foot lever 15a for operating the primary steering rudder 13a. This machine is of the two-seater type, with the control levers 14a and 15a arranged within the fuselage 5a in front of the rear seat 16a. A second set of controlling planes including auxiliary ailerons 16a, auxiliary horizontal rudders or elevators 12a, and auxiliary vertical or steering rudder 13a, are provided to be operated by the student pilot occupying the forward or front seat 16a, said secondary steering and controlling planes 11a, 12a and 13a being provided with suitable manual operating means such as a conventional lever or joy stick 14a for manipulating the ailerons 11a and elevators 12a and an ordinary foot lever 15a for actuating the auxiliary vertical steering rudder 13a. In this type of machine, the instructor pilot may create any desired unfavorable conditions such as might be met with or encountered during actual flight, by manipulating the levers 14a and 15a and actuating the controlling planes operated thereby, the student following the motions thus produced and watching their effects or operating the auxiliary or secondary controlling and steering planes under guidance from the instructor through the medium of levers 14a and 15a so as to receive training in overcoming these unfavorable conditions. As in the embodiment of Figure 1, the primary controlling and steering planes 11a, 12a and 13a have controlling influence or power predominating that of the secondary controlling and steering planes 11a, 12a and 13a. In this type of machine, the instructor pilot is placed in charge of the primary controlling and steering planes having the predominating controlling power or influence, in order that such instructor pilot may

take control of the machine in an emergency and thereby avoid any crash or like disaster.

In the type of machine adapted for actual free flight, such as above described and illustrated in Figures 7 to 9 inclusive, it is desirable to give the advanced training to the student pilot in stages, so that he will not be required to learn to master all of the different controlling planes at one and the same time. For instance, the student pilot may initially be given control of only the auxiliary or secondary ailerons 11⁶, only the secondary elevators 12², or only the secondary vertical rudder 13², and, as the student progresses, he may be placed in charge of two of these controlling planes and then all of them. In order to provide for this training in stages, the type of machine shown in Figures 7 to 9 inclusive may be modified as illustrated in Figures 12 to 19 inclusive. As shown in the latter figures, the lever or joy stick 14² may be mounted on a shaft 28 having an arm 29 rotatably fitted thereon and operatively connected to the auxiliary or secondary ailerons 11⁶. Also, the lever or joy stick 14² may be connected as at 30 with an arm 31 rotatably fitted on a shaft 32 carrying levers 33 operatively connected to the secondary or auxiliary elevators 12², and the foot lever 15² may be carried by a shaft 34 on which is rotatably fitted a lever 35 connected to the secondary or auxiliary vertical steering rudder 13². Means are provided for releasably keying the arms 29 and 31 and the lever 35 to their respective shafts 28, 32 and 34 and respectively including levers 36, 37 and 38 shown in Figures 12 and 13 and respectively detailed in Figures 17, 16 and 18. Each of these levers is pivoted intermediate its ends and is provided at the outer end of one of its arms with an arcuate portion provided with an elongated slot. The arcuate portions of the levers 37 and 38 are respectively indicated at 39 and 40 and their longitudinal elongated slots at 41 and 42, while the arcuate portion of lever 36 is indicated at 43 and its elongated slot at 44, the arcuate portion 43 and its slot 44 of lever 36 being transverse of said lever instead of longitudinally of the latter as with the levers 31 and 38. Slidably carried by the arcuate portion of each of these levers in the longitudinal slot of said arcuate portion is a pin adapted to act as the releasable keying element, the pin of lever 36 being indicated at 36a, the pin of lever 37 being indicated at 37a, and the pin of lever 38 being indicated at 38a. The pin 36a enters an opening in arm 29 and is adapted to be entered into a socket of shaft 28 so as to key the arm 29 to shaft 28, and the same arrangement is illustrated with respect to pins 37a and 38a of levers 37 and 38 in Figures 15 and 14, respectively. As shown, the pin 37a is engaged in an opening of the hub of arm 31 and adapted to enter a socket or recess 45 of shaft 32 and pin 38a is engaged in an opening of the hub of lever 35 and adapted to enter a socket 46 in the shaft 34. Obviously, the levers 36, 37 and 38 may be operated to engage the pins 36a, 37a and 38a in the sockets of their respective shafts 28, 32 and 34, or to disengage them from said sockets to thereby render the levers 14² and 15² operative or inoperative for actuating the controlling planes 11⁶, 12² and 13². The levers 36, 37 and 38 are connected by linkage 47 with an operating lever 48 arranged adjacent the instructor pilot's seat 16a, and any desired one or more of the levers 36, 37 and 38 may be connected to or disconnected from the linkage 47 by means of

removable pins 49 pivotally connecting said levers with the linkage 47. As shown in Figure 19, these pins are readily insertable or removable and may be of any preferred or well known construction, the type shown in Figure 19 with respect to the lever 37 being of the spring cotter pin type. In this way, any desired one or more of the pins 49 may be removed before flight is undertaken, thereby arranging in advance for placing the student pilot only in control of those particular controlling planes which it is desired to give him control of. For instance, the lever 37 may be disconnected from the linkage 47, whereupon said lever 37 will swing by gravity to disengage pin 37a from the shaft 32, thereby rendering the student's lever or joy stick 14² inoperative for actuating the secondary elevators 12². With the levers 36 and 38 connected with the linkage 47, the student pilot will only have control over the secondary vertical rudder 13² and the secondary ailerons 11⁶. In a like manner, the lever 36 may be disconnected from linkage 47 to render the lever 14² inoperative for controlling the ailerons 11⁶, and/or the lever 38 may be disconnected from linkage 47 to render the foot lever 15² inoperative for controlling the secondary steering rudder 13². As the lever 38 is horizontally arranged, a tension spring 50 may be utilized for swinging the lever 38 to disengage its pin 38a from shaft 34 when lever 38 is disconnected from the linkage 47, as shown in Figure 14. It will be particularly noted that whatever controlling or steering planes are operable by the student pilot, will be operatively connected to the lever 48 so that the latter may be actuated by the instructor pilot to take control of these particular planes away from the student pilot in an emergency. For instance, we may assume that the lever 37 is the only one left operatively connected by its pin 49 with the linkage 47, in which case the student will only have control over the secondary elevators 12². This lever 37 will, in that event, be connected to lever 48 so that the latter may be actuated by the instructor pilot for moving lever 37 and disengaging its pin 37a from shaft 32 so as to render the arm 31 inoperative for actuation of lever 33 and the elevators 12² connected therewith, by means of the lever or joy stick 14² held by the student pilot. It is thus apparent that advance training may be given to the student pilot with an arrangement of this kind, in stages or degrees, the number of kinds of controlling planes operable by the student pilot being increased as the student pilot progresses in ability to handle the controls. It will also be apparent that this arrangement enables the instructor pilot to take complete control of the machine whenever necessary. Otherwise, the construction of Figures 12 to 19 inclusive is the same as that of Figures 7 to 9 inclusive, and remaining parts common to both forms are indicated by like reference numerals.

It will of course be understood that under some conditions, as in operating the machine over ice or snow or on the water, a sled runner, pontoon float or the like may be substituted for the ground wheel, and the machine in such case may be driven by an air or water propeller of a suitable type. Any or all such running elements are contemplated by the use of the term "ground wheel" or "ground engaging element."

From the foregoing description the construction, mode of use and advantages of my improved training machine will be readily understood and

appreciated by those versed in the art without a further and extended description.

Although I have described several embodiments of my invention very specifically, it is to be understood that the invention is not limited to the exact details of construction and arrangement of parts illustrated and described, changes being contemplated within the spirit and scope of the invention as claimed.

10. What I claim as new is:

1. A machine adapted to travel on the ground for primary ground training of student pilots in handling airplanes, said machine including a single ground-engaging supporting wheel arranged approximately at the center of gravity of the machine, power means for driving said supporting wheel, a primary set of manually operable controlling planes, a secondary set of controlling planes operable independently of the first-named set, and means for operating said secondary set of controlling planes, said primary set of controlling planes having controlling power predominating that of said secondary set.

2. A machine capable of free travel on the ground for primary ground training of student pilots in handling airplanes, said machine having a single ground-engaging supporting wheel arranged approximately at the center of gravity of the machine, power means for driving said supporting wheel, a primary set of manually operable controlling planes, a secondary set of controlling planes operable independently of the first-named set, said primary set of controlling planes having controlling power predominating that of said secondary set, and power-operated means for actuating said secondary set of controlling planes to create predetermined different adverse flight conditions adapted to be overcome by operation of said primary set of controlling planes.

3. A machine capable of free flight for advanced training of student pilots in handling airplanes, said machine having a primary set of different kinds of controlling planes manually operable only by an instructor, a secondary set of different kinds of manually operable controlling planes operable only by a student and independently of the first-named set, and means to individually disconnect any one kind of the controlling planes in the secondary set from the manual operating means thereof, said primary set of controlling planes having controlling power predominating that of said secondary set.

4. A machine capable of free flight for advanced training of student pilots in handling airplanes, said machine having a primary set of different kinds of controlling planes manually operable only by an instructor, a secondary set of different kinds of manually operable controlling planes operable only by a student and independently of the first-named set, means to individually disconnect any one kind of the planes in the secondary set from the manual operating means thereof, said primary set of controlling planes having controlling power predominating that of said secondary set, and means manually operable only by the instructor or operator of the primary set of controlling planes for disconnecting the kind or kinds of planes of the secondary set which have been left connected to their operating means.

5. A machine capable of free flight for advanced training of student pilots in handling airplanes, said machine having a primary set of different kinds of controlling planes manually operable only by an instructor, a secondary set of different kinds of manually operable controlling

planes operable only by a student and independently of the first-named set, means to individually disconnect any one kind of the planes in the secondary set from the manual operating means thereof, and means manually operable only by the instructor or operator of the primary set of controlling planes for disconnecting the kind or kinds of planes of the secondary set which have been left connected to their operating means.

6. A machine for primary ground training of student pilots in handling airplanes, comprising a fuselage having a single ground-engaging supporting wheel arranged approximately at the center of gravity of the machine, power driven propelling means for the machine, wing-like supports extending laterally from the fuselage, a primary set of manually operable ailerons carried by said wing-like supports, a secondary set of ailerons operable independently of the first-named set and carried by said wing-like supports, means for operating said secondary set of ailerons, said primary set of ailerons having controlling power predominating that of said secondary set, and wheels journaled on the primary ailerons at the trailing edges of the latter and engageable with the ground upon lateral tilting of the machine.

7. A power-propelled machine capable of free travel on the ground for training student pilots in handling airplanes, said machine including wheeled supporting means permitting free longitudinal and lateral tilting of the machine, a primary set of manually operable controlling planes, a secondary set of controlling planes operable independently of the first-named set, said primary set of controlling planes having controlling power predominating that of said secondary set, means for actuating said secondary set of controlling planes to create a plurality of predetermined different adverse flight conditions to be overcome by operation of said primary set of manually operable controlling planes, a motor for driving said last-named means, and means for rendering said last-named means operative or inoperative at will.

8. A power propelled machine capable of free travel for training student pilots in handling airplanes, said machine including a set of manually operable controlling planes, a second set of controlling planes operable independently of the first-named set, means for actuating said second set of controlling planes to create a plurality of predetermined different adverse flight conditions to be overcome by operation of said first-named set of manually operable controlling planes, a driving motor for said last-named means, and means to render said last-named means operative or inoperative at will.

9. A machine capable of free flight for advanced training of student pilots in handling airplanes, said machine having a primary set of different kinds of controlling planes manually operable only by an instructor, a secondary set of different kinds of manually operable controlling planes operable only by a student and independently of the first-named set, an actuating member for each kind of plane in the secondary set, a manually operable operating member for each actuating member, a latching device for connecting each actuating member with its operating member, means to render any desired one of said latching devices inoperative with the associated actuating member disconnected from its operating member, and means manually operable only by the instructor for rendering inoperative

any of the latching devices which have been left operative.

10. A machine capable of free flight for advanced training of student pilots in handling airplanes, said machine having a primary set of different kinds of controlling planes manually operable only by an instructor, a secondary set of different kinds of manually operable controlling planes operable only by a student and independently of the first-named set, an actuating member for each kind of plane in the secondary set, a manually operable operating member for each actuating member, a latching device for connecting each actuating member with its operating member, means to render any desired one of said latching devices inoperative with the associated actuating member disconnected from its operating member, each latching device including a lever, an actuating rod for the levers of said latching devices, and an operating lever for said rod operable only by the instructor for rendering

inoperative any of the latching devices which have been left operative.

11. A machine for primary training of student pilots in handling airplanes, comprising a fuselage having a single surface-engaging supporting element arranged approximately at the center of gravity of the machine, power driven propelling means for the machine, wing-like supports extending laterally from the fuselage, a primary set of manually operable ailerons carried by said wing-like supports, a secondary set of ailerons operable independently of the first-named set and carried by said wing-like supports, means for operating said secondary set of ailerons, said primary set of ailerons having controlling power predominating that of said secondary set, and supporting elements carried by the primary ailerons at the trailing edges of the latter and engageable with the surface upon lateral tilting of the machine.

FREDERICK L. FOX.

20
